UNITED STATES PATENT OFFICE.

ISAAC A. SHEPPARD, OF PHILADELPHIA, PENNSYLVANIA.

DESIGN FOR A COOKING-STOVE.

SPECIFICATION forming part of Design No. 11,881, dated July 20, 1880.

Application filed April 20, 1880. Term of patent 7 years.

To all whom it may concern:

Be it known that I, ISAAC A. SHEPPARD, a citizen of the United States, residing in Philadelphia, Pennsylvania, have invented or produced a new and original Design for a Cooking-Stove, of which the following is a specification.

My design for a cooking-stove is fully shown in the accompanying sheets of illustrations, Sheet 1 being a general photographic view of the stove; Sheet 2, enlarged photographic views of the side doors, and Sheet 3 a view of one of the feet.

The design comprises the oven-door A, fire-place door B, and feet D.

The door A has a flat rim with bead-like border *a* and a raised body, *b*, ornamented with line-work of a character fully illustrated in the photograph, said body having a central upright medallion, *d*, containing a representation of the American flag and the title "Excelsior Cook."

The door B has a flat beaded rim, *f*, and a central raised panel, *g*, with line-work ornamentation, and central medallion, *m*, in the shape of a Maltese cross.

The feet D are of the usual tapering form, the upper portion of each foot being of curved

cross-section, which merges into the rectangular section of the base. Each foot has on the front central portion, *i*, a medallion, *n*, in the shape of a Maltese cross, and other ornamentation, *s*, of a character too fully shown to need detailed description. The upper edge of the foot has a bead, *t*, and the base has an ornament, *w*.

I claim—

1. The design for the door A, said design comprising the border *a*, raised body *b*, with line-work ornamentation, and medallion *d*, with flag and title, as shown and described.

2. The design for the door B, said design comprising the border *f* and raised panel *g*, with line-work ornamentation, and central medallion, *m*, in the shape of a Maltese cross, as shown and described.

3. The design for the foot D, said design comprising the Maltese cross medallion *n* and minor ornamentation, as described and shown.

In testimony whereof I have signed my name to this specification in the presence of two subscribing witnesses.

ISAAC A. SHEPPARD.

Witnesses:

JAMES F. TÓBIN,

HARRY SMITH.
